ATTORNEY.

UNITED STATES PATENT OFFICE.

JOHN R. GAMMETER, OF AKRON, OHIO.

RUBBER HEEL.

Application filed July 18, 1928. Serial No. 293,515.

This invention relates to rubber heels and has for its object to provide improved means embedded within the heel body for retaining the heads of the attaching nails.

5 While the retaining device which I employ might be incorporated in the heel body during the molding process, one of the advantages of the invention in its preferred form consists in the fact that the retaining means may be 10 located in the heel after the latter has been vulcanized.

Of the accompanying drawings:

Fig. 1 is a horizontal section on the line 1—1 of Fig. 2 showing a preferred form of my 15 proved heel.

Fig. 2 is a transverse section thereof on line 2—2 of Fig. 1.

In the drawings, 10 is a rubber cushion heel body which may be vulcanized in its final 20 form in a mold without any inserts or nail retaining structure. After the molding process the heel body is provided with a series of parallel narrow holes or wire sockets 11, open at one end at the breast edge 12, these sockets 25 being spaced apart a distance less than the width of the heads of the nails 13 used for attaching the heel to the shoe. In the sockets are mounted a series of individual or isolated, metallic rods or wires 14, preferably of high- 30 carbon steel of about .037 inch diameter to serve as a nail-retaining means.

While it would be possible to use wire mandrels in the mold for forming the sockets 11 during the process of vulcanization, I prefer, 35 as stated, to make the sockets after the heel has been vulcanized. This may be done with a piercing operation, without substantial removal of stock, by employing drills which tear their way through the vulcanized rubber. 40 The drills are somewhat larger in diameter than the wires 14, and when withdrawn they leave holes with rough walls which practically close together.

After forming the sockets 11, the wires 14 are forced into said sockets until their trailing ends have receded within the heel body a short distance from the breast edge 12 as indicated in Fig. 1, these wires being of graduated lengths so that their rear ends collective-

ly assume a curved or arcuate formation, substantially parallel to the edge contour of the heel.

The heel may be molded with vertical apertures extending to the wires 14, for receiving the nails, or the heel body may be left solid and the nails driven therethrough until their heads encounter the wires, as represented in Fig. 2. Since the wires have a closer spacing than the diameters of the nail heads, they constitute an effective retaining means. The structure is such that the position of the nails within the field of wires is immaterial, for, if a nail point happens to strike a wire it will glance off and continue through with but very little relative displacement. In this respect 65 my invention presents a decided advantage over the use of embedded washers where any substantial misalignment of the entering nails with the apertures in the washers will spoil the attachment. Molding the heel without washers enables me to employ a machine-filled mold which opens at the seating face so that the flash may be buffed off while the heels are still in the mold cavities.

It will be understood that suitable variations may be effected in the precise mode of carrying my invention into effect without departing from the scope of the claims.

I claim:

1. A rubber heel having a nail-head retaining structure comprising a multiplicity of individual embedded wires collectively adapted to retain the heads of nails inserted in a zone surrounding the central portion of the heel.

2. A rubber heel having a nail-head retaining structure consisting of a series of closely spaced, parallel, individual wires embedded in the heel body.

3. A rubber heel comprising a rubber cushion body formed with a series of closely-spaced, parallel wire sockets opening on the breast edge of the heel, and individual wires occupying said sockets and terminating at their forward ends short of said breast edge.

In witness whereof I have hereunto set my hand this 17th day of July, 1928.

JOHN R. GAMMETER.
